PRESS WITH HYDRAULICALLY CONTROLLED BLANK HOLDER

David C. Verson, Chicago, Ill., assignor to Verson
Allsteel Press Company, Chicago, Ill., a corpora-
tion of Delaware

Application April 26, 1943, Serial No. 484,505

18 Claims. (Cl. 113—45)

1

My invention relates to presses. More particularly, it relates to so-called "double acting" presses wherein one reciprocable slide (which for convenience may be termed the "work slide") carries a punch or die for performing the desired operation upon the work piece, and another slide (which for convenience may be called the "blank holder slide") effects the retention of the work piece in position during such operations as drawing.

One of the objects of my invention is to provide an improved double acting press.

Another object is to provide a press wherein the punch or die actuating (i. e., work) slide is of the so-called mechanical type (i. e., driven by a crank, eccentric or the like) and the work is held in place by fluid pressure. There is thus combined advantages of the mechanical press, such as speed, and also advantages of holding the work with constant and easily adjustable and flexible fluid pressure.

Another object is to provide a press wherein the work is retained in position by hydraulic pressure applied at a plurality of points in such manner as to compensate for variations in work thickness, distortion of the press frame which may occur under extreme forming pressures, and other conditions which might result in the work being ineffectively held.

A further object is to provide adequate movement of the blank holder slide with a small movement of hydraulic fluid.

An additional object is effectively to retain the work in place under high clamping pressure with little power in addition to that required to do the desired work.

Another object is to provide for the more effective "stripping" of the punch or die from the work.

A further object is to provide a more effective release and elevation of the blank holder from the work.

A further object is to afford protection to press parts against shock when the blank holder is moved from clamping position.

Other objects and advantages will hereinafter appear.

The invention is shown and will be described or embodied in a press equipped with a rectangular blank holder for performing a drawing operation to produce a rectangular box-like structure.

In the drawings,

Fig. 1 is an end elevation in partial section of an embodiment of my invention incorporated in

5 a press which, for sake of simplicity, is largely fragmentary and diagrammatic;

Fig. 2 is an enlarged plan in partial section;

Fig. 3 is an enlarged vertical section of the 5 hydraulic system for operating the work holder to clamp the work in position in the press, and

Fig. 4 is an enlarged vertical section of the 10 hydraulic system for elevating the work holder from the work.

In general the press comprises a frame A, of 15 which only enough to make clear the application of the present invention is shown, a stationary die B, a reciprocable work slide C carrying a punch or die D, a mechanical arrangement E for reciprocating the work slide, exemplified by a crank 5 and a connecting-rod 6, and a rectangular reciprocable blank holder slide F. Associated with these usual elements of a common variety of power press are the hydraulic system G for actuating the blank holder slide whereby the work is clamped in position to be operated upon by the punch and die, and a hydraulic system H for insuring proper stripping of the punch from the finished work, and for releasing the work and returning the blank holder to initial or work receiving position after the punch has been forced or stripped from the work. In the embodiment chosen for purposes of illustration, the work slide travels twice as far both up and down 20 as does the blank holder slide. Thus, for example, the work slide may travel fifty inches from the top to the bottom of its stroke, whereas the vertical movement of the work holder slide is only approximately twenty-five inches. Of course, the slides are guided and laterally supported by suitable ways on the frame, but they have been omitted from the drawings in order not to complicate the disclosure with mechanism extraneous to the invention.

In the press shown, each of the two hydraulic 25 systems acting upon the rectangular blank holder slide consists of four similar units so that only one unit of each system needs be described in detail.

45 Referring particularly to Fig. 3, one unit of the hydraulic system G for moving the blank holder slide F to and against the work piece and then causing this slide to clamp the work piece so as to retain the work in position sufficiently 50 to enable the desired operation to be performed upon it and yet permit it properly to flow from the edges during the drawing operation performed thereon will be described in detail.

Blank holder slide F is mounted to reciprocate 55 vertically in the press frame. On the down

stroke it presses the rim of the work piece 9 tightly but not absolutely immovably against the blank seat 10, which is usually a part of the die, and then continues to clamp it there during the drawing operation. It carries a tubular plunger 11 which is rigidly attached thereto in any suitable manner as by welding. Plunger 11 telescopically extends into a sleeve 12 which is rigidly carried by the work slide C so as to reciprocate therewith under the drive of the crank and connecting-rod 5-6. Sleeve 12 is, except for an internal packing-seat flange 13 near its lower end, of slightly larger internal diameter than the external diameter of plunger 11. Suitable packing 14, held in place and compressed against flange 13 and plunger 11 by a cap-screw retained gland 15, provides a liquid-pressure tight fit between the plunger 11 and sleeve 12. Bolted to the upper end of sleeve 12 is a tubular plunger 20, the internal diameter of which is somewhat smaller than the diameter of plunger 11 so as to form a stop to limit the amount of telescopic movement of the latter into the bore of sleeve 12. Plunger 20 telescopes into the cylindrical bore of a bracket 21 which is suitably rigidly attached in a stationary position on the press frame. Packing 22 and a gland 23 serve to provide a fluid-pressure tight but sliding fit between bracket 21 and plunger 20. The upper end of cylinder 21 is closed by a head 24 secured thereto by cap screws 25. Head 24 has a cylindrical dome 26 formed integrally therewith and which houses the operating mechanism for a valve 27. A casing 28 is tightly fitted and secured to head 24 in any appropriate manner as by welding to form an oil storage reservoir. Dome 26 is divided into two compartments by a partition 30 through which the stem 31 of valve 27 slides. The lower compartment of dome 26 is in constant communication with oil reservoir 28 through ports 32 and valve 27 controls a port 33, which extends through head 24 to afford communication between the lower compartment and the bore of sleeve 21. The upper compartment of dome 26 is in constant communication with the interior of reservoir 28 through ports 35 and in its fits a reciprocating piston head 36 which is attached to the upper end of valve stem 31. Light biasing springs 37 urge the valve 27 upwardly to closed position preferably with a force only slightly more than that required to counterbalance the weight of the valve and other moving parts. Suitable packing or sealing rings should be interposed between the outer wall of piston head 36 and the inner wall of the upper compartment of dome 26 to prevent leakage therebetween of oil under such pressures as may exist. An air pressure pipe 40 is threaded into an opening through the upper head of dome 26 so as to enable air pressure of about 80 pounds per square inch from a compressed air storage tank 41 to be imparted to the upper chamber of the dome above piston head 36. This air connection is opened and closed by a solenoid valve 42 whose function and operation will be subsequently explained. A pipe 43 screwed into an opening through head 24 and a pipe 44, which is in communication with reservoir 28, provide a liquid connection between the reservoir 28 and the interior of the piston cylinder combination 21, 20, 12 and 11. This liquid connection is controlled by a solenoid pressure release valve 45 whose function and operation will be subsequently explained.

Attached to stationary sleeve 21 by a bracket 46 is an air cylinder 47. Slidably mounted in

cylinder 47 is a reciprocable piston 50 having a pressure-tight sliding fit within the bore of cylinder 47. This piston carries a stem 51 which slidably fits within the vertical portion of a passage 53 that opens into the bore of sleeve 21. Suitable packing and a gland 54 insure a tight but sliding fit between valve stem 51 and the bore of passage 53. The lower chamber of cylinder 47 which is defined by the movable piston 50 is vented to atmosphere through ports 55; and the upper compartment 56 above the piston 50 is permanently connected by a pipe 57 and through a pressure control valve 58 to the air storage tank 41 so that piston 50 is subjected always to downwardly directed air pressure the force of which depends upon the setting of control valve 58. At maximum this pressure, in the instance given, is 80 pounds per square inch. The relative areas of piston 50 and its stem 51 are preferably such that, for example, the 80 pounds per square inch of air pressure supplied above the piston from tank 41 can exert a pressure—or perhaps more accurately expressed—resist a pressure of 2000 pounds per square inch exerted upwardly against the bottom of stem 51. Under such conditions the blank holder slide can exert, as a maximum, a pressure of 2000 pounds per square inch upon the work blank as will be hereinafter explained.

The closing and opening of solenoid valve 42 is effected in the well-known manner by an electrical circuit which includes a switch 60. By means of this switch the energization and de-energization of the operating solenoid of valve 42 is brought about and timed in relation to the stroke of work slide C by a cam 61 (see Fig. 1). When switch 60 is closed the solenoid of valve 42 is energized and the valve is closed. When valve 42 is open, air under pressure from tank 41 is permitted to flow into the upper compartment of dome 26 and exert a downward pressure upon piston 36 to open valve 27. Cam 61 is driven in some suitable manner such, for example, as a one-to-one ratio chain and sprocket wheel connection from the shaft of crank 5. In like manner, the opening and closing of the liquid relief valve 45 is effected by a solenoid, the energization and de-energization of which is brought about and timed by a switch 63 acted upon by a cam 64, also driven from the shaft of crank 5. It is, of course, to be understood that where the hydraulic system G for depressing the blank holder is, as in the case of the press shown, composed of a number of units, the solenoid switches of all units needs be connected in multiple to only one set of switches 60 and 63 so that the units of the system will operate in unison.

The pressure effective areas of tubular plungers 11 and 20 with respect to each other and to the internal cross sectional areas of sleeve 12 and the bore of bracket 21 are so related that when the internal chamber formed by them is filled with liquid (e. g., oil) and plungers 11 and 20 move relative to each other, there is a small volume differential between their respective displacements. The differential should be such that through a given relative movement plunger 11 will displace a greater volume of liquid than plunger 20 whereby a pressure will be built up to act against the stem 51 of piston 50 in opposition to the air pressure existing above piston 50. For example, this differential may be such that for every inch of travel, plunger 11 will displace approximately four cubic inches more liquid than will plunger 20.

Referring now to Fig. 4, one unit of the companion hydraulic system H for insuring retention of the blank holder in blank clamping position until the punch has been stripped from the work and for thereafter elevating the blank holder to condition the press for the reception of another work piece will now be described. Only one needs be described because, although the press is shown equipped with four, all are identical. The blank holder F carries rigidly attached thereto a pair of parallel oppositely opening or acting hydraulic cylinders 65 and 66, the latter being attached to the slide F through a bracket 67. Slidably mounted in the cylinders are pistons 68 and 69, respectively. Pistons 68 and 69 are rigidly attached to work slide C. Thus, whenever there is relative movement between the work and blank holder slides, one of the pistons 68-69 is moved further into its cylinder, while the other piston is retracted in its cylinder, which piston is going in and which is going out depending upon the direction of relative movement between the work and blank holder slides. Suitable packing and packing glands 70 and 71 serve to provide pressure-tight but sliding fits between pistons 68 and 69 and their respective cylinders 65 and 66. A pipe 75 in which is interposed a solenoid valve 76 serves as a liquid connection between the chambers of cylinders 65 and 66, such connection being opened and closed by the de-energization and energization, respectively, of its solenoid winding. A branch pipe 77 leads to the bore 78 in the base of a shock absorber cylinder 79. A piston 80 slidably fits the upper cylindrical chamber of cylinder 79, suitable rings serving to insure a pressure-tight fit therebetween. The stem 81 of piston 80 fits the bore 78 and is acted upon from below by the liquid supplied through branch pipe 77. Air pressure is applied through pipe 82 from air pressure tank 41 to chamber in cylinder 79 above piston 80 so that the piston is always pressed downwardly by a constant air pressure that may, if desired, be varied by a pressure control valve 83. A small liquid pipe 85 leads from the space below piston stem 81 to a pressure actuated safety switch 86. This safety switch may, in a well known manner, effect the actuation of a solenoid controlling the operation of the entire press either through a clutch or a switch in the press-motor circuit. The hydraulic system, including the cylinders 65 and 66 and the bore of the shock absorber 79 below the piston stem 81 is filled also with oil. As long as solenoid valve 76 is opened, this oil may circulate freely between cylinders 65 and 66 through pipe 75; then pipe 68 may freely move further into its cylinder 65 and at the same time plunger 69 may move freely out of cylinder 66 and vice versa. On the other hand, when valve 76 is closed and there can be no free transfer of oil between cylinders 65 and 66, the work slide C and the blank holder slide F are in effect interlocked so that they move together. If, however, work slide C is moving upwardly and blank holder slide F is stationary when valve 76 is closed, there can still be some slight further movement of plunger 69 into cylinder 66, thereby permitting the continuance of some degree of relative movement between the work and blank holder slides, because such movement will build up a liquid pressure in branch pipe 77, and the chamber below the stem 81 of piston 80, opposing the air pressure against the top of piston 80. Relative movement between the work and blank holder slides will thus

continue until the liquid pressure built up by the continuing movement of piston 69 into cylinder 66 balances the effect of the air pressure above piston 80 in the safety cylinder 79. A cushion is thus provided between the work slide C and the blank holder slide F for a purpose to be later explained.

Solenoid valve 76 is controlled by a switch 90 which, in a manner similar to switches 60 and 10 63, is controlled by a cam 91 driven from crank shaft 5. When switch 90 is closed, solenoid switch 76 is closed to close the liquid connection between cylinders 65 and 66.

The complete operation of the press will now be explained. Assuming that the crank shaft is at the top of its stroke, the work slide C, the blank holder F and the telescopic cylinder-plunger system 11-12-20-21 will be in the respective positions indicated by the dotted lines of Fig. 3—work slide C say 50 inches above its lowermost position and blank holder slide F approximately 25 inches above its lowermost position. During the subsequent first quarter of a revolution of the crank—i. e., while it is moving clockwise as indicated by the arrow—from its top position to the position shown in Fig. 1, the work slide C moves down toward the work half of its travel. Also the blank holder slide F is carried with the work slide to the full extent of the downward travel of the blank holder slide and against the work piece. During this first quarter of a revolution of the crank, the work and blank holder slides are caused to travel together because from the beginning to the end of this quarter revolution the switch 90 controlling solenoid valve 76 has been closed and retained closed. Therefore, solenoid valve 76 is closed and the flow of oil between cylinders 65 and 66 is prevented. Thereafter the work and blank holder slides have been effectively interlocked and both have traveled downwardly together. However, a very short interval before the blank holder strikes the work piece, cam 91 may open switch 90 so as to de-energize solenoid valve 76 and permit it to open. During this first quarter cycle, the cam 61 is always in such relation to switch 60 that this switch remains open. Solenoid valve 42 is therefore de-energized and open and oil from the reservoir 28 flows into the hydraulic plunger-cylinder system 11-12-20-21 in sufficient amount to compensate for the withdrawal of plunger 20 from the bore of bracket 21. Thus this telescopic hydraulic plunger system is retained full of oil. Also during this first quarter of crank shaft rotation, the cam 64 holds the contacts of switch 63 closed so that the solenoid of liquid relief valve 45 is energized and this valve is held closed so that no oil flows between reservoir 28 and the bore of bracket 21 through the pipes 43 and 44.

When the crank shaft has completed its first quarter phase of rotation and enters upon its second phase, the cam 61 closes switch 60 with the result that valve 42 is energized and closes 65 so that air pressure from tank 41 is removed from the back of the piston valve 27. Thereupon valve 27 will close as soon as pressure starts to build up in the hydraulic-cylinder plunger system 11-12-20-21; and that pressure begins 70 at once to build up because the blank holder slide being down against the work and therefore incapable of further downward movement, the plunger 11 begins to telescope into the still downwardly traveling sleeve 12. The volume differ-

ential between the positive displacement caused by sleeve 12 traveling down over plunger 14, and the negative displacement caused by plunger 20 moving out of the bore of bracket 21, builds up a pressure below valve 21 to close it and below the stem 51 of piston 50, tending to elevate that piston against the air pressure from tank 44. Thus, the pressure exerted downwardly against the work piece by blank holder slide F builds up until there is a balance between the internal pressure in the cylinder-plunger system 11-12-20-21 and the downward air pressure exerted against piston 50, in the illustrated example being 2000 pounds per square inch. In this manner, by the time the punch carried by work slide C has started to perform the desired operation upon the work piece, that work piece is tightly clamped by the blank holder slide and continues so to be clamped throughout the drawing operation which is performed by the punch during the second quarter phase of the rotation of its actuating crank. The clamping of the work piece, however, is somewhat resilient due to the cushioning effect of the air pressure behind piston 50, which actually controls the pressure exerted by the work holder slide upon the work piece. Throughout this second phase of crank rotation, switch 90 remains open so that valve 16 is open and oil can freely circulate between cylinders 65 and 66 to permit the necessary relative movement between the work and blank holder slides. Switch 63 remains closed so that valve 45 remains closed throughout the second quarter phase of crank rotation.

During the third quarter phase of crank rotation, i. e., as the work slide C rises after completion of the operation of the work piece, cam 61 continues to hold switch 60 closed so that valve 42 remains closed and in consequence, valve 27 is held closed by the pressure built up and remaining below it. Thus, although the work slide rises, the blank holder slide is held down to retain the work piece in position and proper stripping of the punch from the work is insured. To permit this relative movement between the work and blank holder slides, switch 90 remains open to keep valve 76 open and thereby permit a free exchange of oil between cylinders 65 and 66.

As the fourth and last quarter of crank rotation commences, valve 45 is opened by cam 64, permitting switch 63 to open. The opening of valve 45 permits oil to flow from the until then closed cylinder-plunger system 11-12-20-21 to reservoir 28, effecting a release of the liquid pressure below valve 21. At the same time cam 61 opens switch 60 which energizes the solenoid switch 42 to permit pressure from tank 44 to act upon the back of piston 36. This air pressure tending to open valve 27, coupled with the relief of opposing pressure effected by the opening of valve 45, enables valve 27 to open. Cam 91 has closed switch 90 and holds it closed during the last quarter phase so that valve 76 is energized and closed and flow of oil between cylinders 65 and 66 is prevented. Therefore, as previously explained, the slides move together during the last quarter phase of crank rotation and the blank holder slide is raised to the position assumed at the beginning of a cycle of press operation.

The resiliency of the air column in cylinder 47, which controls the pressure exerted on the work piece by the blank holder slide, enables the blank holder to accommodate itself to some

variations in the thickness of the work in different places and still effect proper distribution of clamping pressure. The resiliency of the air column in cylinder 79 cushions the starting of the relative movements between the work and blank holder slides and so relieves the mechanism from undue shock. In the event the pressure in cylinder 66 tends to become unduly high, it operates safety switch 85 to stop the press.

Having thus explained the nature of my invention and described a typical embodiment thereof, what I claim and desire to secure by United States Letters Patent is as follows:

1. A punch press having a crank driven work slide and a blank holder slide, characterized by an hydraulic system for interlocking the two slides, said system including a pair of reversely acting cylinder-plunger sets connected to the two slides, so that as one set expands, the other set contracts when relative movement occurs between the two slides, a fluid connection between the cylinder-plunger sets so that liquid may transfer from the contracting to the expanding set to permit relative movement therebetween, a solenoid valve in the fluid connection to prevent transferring of liquid and thereby interlock the two slides, a circuit including a switch for controlling the valve, and a cam driven by the crank shaft for timing the opening and closing of said switch.

2. A punch press having a crank operated work slide and a blank holder slide, characterized by an hydraulic pressure system actuated by the work slide for actuating the blank holder slide to cause it to clamp the work, an hydraulic system for interlocking the two slides to cause them to move together, solenoid operated valves for controlling the two hydraulic systems, circuits including switches for controlling the solenoid valves, and cams operated from the work slide crank to open and close the contacts.

3. A punch press having a mechanically driven work slide in combination with a blank holder slide, an hydraulic system for pressing the blank holder slide in work clamping position, the pressure in the hydraulic system being built up by the movement of the slide toward the work after the blank holder has reached clamping position, and another hydraulic system for raising the blank holder slide out of work clamping position, the second mentioned hydraulic system interlocking the blank holder slide and the work slide during that portion of an operation cycle when the blank holder slide is being moved toward and away from work clamping position.

4. A punch press having a crank driven work slide and a blank holder slide, characterized by an hydraulic system for interlocking the two slides, said system including a pair of reversely acting cylinder-plunger sets connected to the two slides, so that as one set expands, the other set contracts when relative movement occurs between the two slides, a fluid connection between the cylinder-plunger sets so that liquid may transfer from the contracting to the expanding set to permit relative movement therebetween, a valve in the fluid connection to prevent transferring of liquid and thereby interlock the two slides, and means actuated by the crank shaft for timing the opening and closing of said valve.

5. A punch press having a mechanically driven work slide in combination with a blank holder slide, an hydraulic system for interlocking the work slide and the blank holder slide when the blank holder slide is moving toward and away

from work clamping position, a valve for controlling the flow of fluid in the hydraulic system, and timing means actuated by the mechanical drive and operating said valve to render the hydraulic system effective during a portion of a cycle to lock the blank holder slide to the work slide for movement to and from work clamping position, and during another portion of the cycle to interlock said slides to permit relative movement between said slides.

6. A punch press having a mechanically driven work slide in combination with a blank holder slide, means connecting the work slide and the blank holder slide and permitting relative movement therebetween, and hydraulic system actuated by the work slide for actuating the blank holder slide to cause it to clamp the work, a valve controlling the creation of pressure in the hydraulic system, another hydraulic system forming a portion of the means connecting the work slide and the blank holder slide, a valve in the second mentioned hydraulic system for preventing flow of fluid therethrough to interlock the work slide and the blank holder slide, and timing means operated by the mechanical drive for each valve to open and close the valves in unison with the movement of the work slide.

7. A punch press having a mechanically driven work slide in combination with a blank holder slide, an hydraulic system for pressing the blank holder slide in work clamping position, another hydraulic system adapted to connect the blank holder slide with the work slide, a valve for controlling the flow of fluid in said second hydraulic system, and timing means operable in unison with the reciprocation of the work slide to operate said valve to render said second hydraulic system effective to interlock the blank holder slide and the work slide to cause the latter to advance and withdraw the former to and from the work clamping position, said valve being operable by said timing means to render said second hydraulic system inoperative so as to break the interlock when the blank holder slide is in the work clamping position to permit relative movement between the blank holder slide and the work slide.

8. A punch press having a mechanically driven work slide in combination with a blank holder slide, an hydraulic system for pressing the blank holder slide in work clamping position, another hydraulic system adapted to connect the blank holder slide with the work slide, a valve for controlling the flow of fluid in said second hydraulic system, timing means operable in unison with the reciprocation of the work slide to operate said valve to render said second hydraulic system effective to interlock the blank holder slide and the work slide to cause the latter to advance and withdraw the former to and from the work clamping position, said valve being operable by said timing means to render said second hydraulic system inoperative so as to break the interlock when the blank holder slide is in the work clamping position to permit relative movement between the blank holder slide and the work slide, and means including timing means operable in unison with the reciprocation of the work slide to relieve the pressure in the first hydraulic system while the blank holder slide is being withdrawn from the work clamping position.

9. In a double action press, a mechanically reciprocable die slide mechanism, a reciprocable work clamping mechanism, hydraulic mechanism operatively disposed between and adapted to in-

terlock the work clamping mechanism immovable with respect to the die slide whereby one of said slides moves the other, a control system for the hydraulic mechanism operable upon predetermined reciprocation of one of said slides to render said hydraulic mechanism operative and inoperative for connecting and disconnecting the work clamping mechanism from the die slide, and means independent of said interlocking mechanism interconnecting the die slide and the work clamping mechanism and the frame of the press for exerting pressure from the die slide upon the work clamping slide when the die slide is operatively disconnected from the work clamping slide by said control system.

10. In a press, a mechanically reciprocable slide, a work holding slide mechanism, hydraulic mechanism connecting the work holding mechanism to the reciprocable slide whereby the two slides are adapted to move in unison during a part of the cycle of an operation thereof, a control system for the hydraulic mechanism operable to permit movement of one of the slides while movement of the other slide is arrested, a differential duplex piston and cylinder mechanism interposed between the slides for exerting hydraulic pressure upon the arrested work holding mechanism and during movement of the other slide, and means associated with the piston and cylinder mechanism for maintaining the pressure therein uniform during the arrested period of said holding slide mechanism.

11. In a press, a mechanically reciprocable slide, a second slide mechanism, a controllable locking mechanism operatively disposed between and connecting the second slide mechanism to the reciprocable slide whereby the two slides are adapted to move in unison during a part of a cycle of an operation thereof, a control system for the locking mechanism operable to permit movement of one of the slides while movement of the other slide is arrested, a piston and cylinder mechanism interposed between the slides for exerting hydraulic pressure upon the arrested second slide mechanism and during movement of the other slide and whereby the pressure is generated by such relative movement, and means associated with the piston and cylinder mechanism for maintaining the pressure generated therein constant during relative movement between the two slide mechanism.

12. In a double action press the combination of a die slide, a clamping slide, a hydraulic locking mechanism connecting the clamping slide to the die slide, valve means for controlling said hydraulic locking mechanism whereby the relative vertical position of the die slide and the clamping slide can be varied as desired during the raising and lowering of said slides, a shock absorber means associated with the hydraulic locking mechanism for protecting the clamping slide when downward movement thereof is arrested by a work blank, a hydraulic piston and cylinder mechanism mechanically connected to the die slide and the clamping slide and to the frame of the press for generating pressure exertable upon the clamping slide during relative movement of the slides, means for maintaining such generated pressure uniform, and control means for breaking the pressure in the piston and cylinder mechanism prior to initiation of an upward movement of the clamping slide.

13. In a press the combination of a mechanically actuated slide, a second slide raised and lowered by the first named slide, means for recip-

rotating one of said slides, an intermittently operable locking mechanism connecting the two slides, a control mechanism operable upon reciprocation of one of said slides for effecting disconnection of the slides during part of the cycle of action of the mechanically actuated slide, a duplex hydraulic piston and cylinder differential mechanism interconnected between the two slides including a piston and cylinder carried by the mechanically actuated slide for generating pressure upon the second slide during relative movement between the slides, means for maintaining such generated pressure at a predetermined constant value, and a pressure breaker mechanism operable prior to the locking action of said locking mechanism.

14. In a double action press, a die slide; a work clamping slide, said slides being movable relative to one another, means for reciprocating one of said slides, means for interlocking said slides in a plurality of selected, relative positions whereby said slides are movable as a unit in opposite directions during predetermined movements of said slide, said interlocking means including, two fluid containing cylinders each having a piston reciprocable therein, said cylinders and their cooperating pistons being carried by opposite of said slides whereby the cylinders and pistons are moved relative to one another when said slides are moved relative to one another, said cylinders and pistons being arranged so that when one piston is withdrawn relative to its cooperating cylinder the other of said pistons is telescoped relative to its cooperating cylinder, conduit means interconnecting said cylinders whereby fluid is transferable from one cylinder to the other when said slides are moved relative to one another, and a valve for controlling the flow of fluid through said conduit means.

15. In a double action press, a mechanically reciprocable slide mechanism, a reciprocable work clamping mechanism, a hydraulic mechanism adapted to connect the work clamping mechanism to the die slide during part of the cycle of operation of said slides, a control system for the hydraulic mechanism operable upon reciprocation of one of said slides to hydraulically disconnect the work clamping mechanism from the die slide, a duplex differential piston and cylinder mechanism interconnecting the die slide and the work clamping mechanism and the frame of the press for exerting pressure upon the work clamping slide when the die slide is operatively disconnected from work clamping slide by said control system, and means operable during said pressure exertion for maintaining a constant volume, uniform pressure condition in said piston and cylinder mechanism.

16. In a sheet metal drawing press, the combination of a press frame, a drawing die slide, a blank holder slide, mechanical means for reciprocating the die slide, pressure generating hydraulic mechanisms operatively disposed between the two slides and located at opposite sides of the die slide and operable to generate pressure when relative movement between the two slides takes place, a hydraulic locking device operatively connected to the two slides whereby the slides may be moved in unison and also may be moved relative to each other, valve means controlling the locking device whereby the die slide can raise and lower the blank holder slide during part of the cycle of operation of the die slide, means operated in synchronism with one of said slides adapted to operate said valve means to hydraulically

disconnect the two slides when the blank holder is lowered into contact with a work blank, a constant pressure constant volume maintaining means associated with each of the pressure generating hydraulic mechanisms for maintaining a predetermined uniform pressure upon the blank holder slide during both a downward and upward movement of the die slide, a fluid reservoir associated with each of the pressure generating hydraulic mechanisms for receiving fluid from and supplying fluid to said mechanisms when the two slides are being moved in unison, valve means controlling said reservoir supply and controllable in synchronism with one of said slides, and a pressure breaking means associated with the reservoir supply and the pressure generating hydraulic mechanisms for breaking the pressure upon the blank holder slide before the die slide is hydraulically locked to the blank holder slide during an upward movement of the die slide.

17. In a sheet metal drawing press, the combination of a press frame, a drawing die slide, a blank holder slide, mechanical means for reciprocating the die slide, pressure generating hydraulic mechanisms operatively disposed between the two slides and located at opposite sides of the die slide, a hydraulic locking device operatively connected to the two slides, valve means controlling the locking device whereby the die slide can raise and lower the blank holder slide, a shock absorber means associated with the locking device for absorbing shock when movement of the blank holder slide is being arrested, means operated in synchronism with one of said slides adapted to operate said valve means to hydraulically disconnect the two slides when the blank holder is lowered into contact with a work blank, a constant pressure constant volume maintaining means associated with the pressure generating hydraulic mechanisms for maintaining said predetermined pressure upon the blank holder slide during part of a downward and upward movement of the die slide, a fluid reservoir associated with the pressure generating hydraulic mechanisms when the two slides are being moved in unison, valve means controlling said reservoir supply and operable in synchronism with one of said slides, and a pressure breaking means associated with the reservoir supply and the pressure generating hydraulic mechanisms for breaking the pressure upon the blank holder slide before the die slide is hydraulically locked to the blank holder slide during an upward movement of the die slide.

18. A punch press having a reciprocable crank driven work slide and a blank holder slide, characterized by a three part hydraulic plunger-cylinder combination with one part attached to the work slide, another part attached to the blank holder slide and a third part secured immovably to the press frame, the relative displacement of the parts being such that when relative movement takes place therebetween because of the advance of the work slide an hydraulic pressure is built up therein to hold the blank holder slide against the work, a source of fluid under low pressure for the three part plunger-cylinder combination, a valve controlling fluid flow between the source and the three part plunger-cylinder combination and arranged so as to be held in closed position by pressure built up in the three part plunger-cylinder combination, valve operating means, timing means con-

13

trolling the valve operating means and timed to the press cycle to render said valve operating means operative to open the valve during that part of the press cycle when the blank holder slide is moved toward and away from the work and to render said valve operating means inoperative during the blank holding part of the cycle so that the valve is held in said closed position, a pressure limiting control system for the three part plunger-cylinder combination including a pneumatic cylinder having a pneumatic pressure biased plunger therein and an hydraulic cylinder having an hydraulic pressure biased plunger therein connected to the pneumatic plunger, the hydraulic cylinder being in constant communication with the three part plunger-cylinder combination so that the pressure acting against the hydraulic plunger is always the same as the hydraulic pressure in the three part plunger-cylinder combination and is connected to uphold the pressure in the pneumatic cylinder, whereby the pressure in the three part plunger-cylinder combination is limited by the pressure in the pneumatic cylinder and the pressure exerted by the blank holder slide is controlled by said pneumatic pressure, and a normally closed pressure relief valve positioned between the fluid source and the three part plunger-cylinder combination and timed to the press cycle to open at

14

the end of a blank holding operation thereby to relieve the pressure built up in the three part plunger-cylinder combination and timed to close at the end of the press cycle to condition the three part plunger-cylinder combination for a succeeding operation.
